UNITED STATES PATENT OFFICE

CHARLES E. REDDIG, OF KEW GARDENS, NEW YORK, ASSIGNOR TO GRAYBAR ELECTRIC COMPANY, OF NEW YORK, N. Y., A CORPORATION OF NEW YORK

IRONING MACHINE

Application filed August 31, 1927. Serial No. 216,503.

This invention relates to an ironing machine primarily adapted for household use, and more particularly to the combination of such a machine with a kitchen table.

5 The invention has for its primary object to provide a combined structure answering the demand for space conservation in the modern kitchen by combining with an ironing machine for general domestic ironing a 10 kitchen table. A further object is to conceal from view that portion of the apparatus used exclusively for the ironing when it is not in use, at the same time protecting it from dust and mechanical injury.

15 A further object is to provide means for driving the work supporting roll independently of the ironing shoe operating mechanism, and to conceal the roll driving means from view.

20 A still further object is to provide power means for moving the heated ironing shoe into and out of operative relation with the roll independently of the actuation of the roll.

25 Fig. 1 is a side elevation of a preferred form of combined ironing machine and kitchen table, as the latter normally appears when the ironing machine is not in use;

Fig. 2 is a similar view, partially broken 30 away showing the structure when the ironer is in use;

Fig. 3 is a front view of the combined structure when the ironing machine is in use;

Fig. 4 is a longitudinal section through 35 the work supporting roll showing the drive mechanism for the roll;

Fig. 5 is an end view, partially schematic, in which is shown the power drive for the ironing shoe;

40 Fig. 6 is a rear view of the shoe operating mechanism, partially broken away.

Reference being had to the drawings, the frame side members 10 and 11 are connected and spaced at their bases by the tie rods 12 45 and the rotatable shaft 13. The side members 10 and 11 have rearwardly extending arms 14 which support the ironing roll 15. The ironing shoe 16 is rigidly connected to the shaft 13 by means of the shoe supporting 50 levers 17, but is capable of oscillating about

the upper ends of said levers. The table legs 18 are connected to the frame end members 10 and 11 and the upper front closure member 19 is secured to the front pair of legs. A trough 20 extends from below the rotatable 55 shaft 13 upwardly to the front of the machine leaving the opening 21 at the front of the table. The opening immediately below the curved trough 20 thus permits the operator to get as close to the machine as desired 60 by providing clearance for his knees. The feed table 22 is pivotally hinged to the upper closure member 19 and is of a width sufficient to completely cover the opening 21 when the said feed table is folded downwardly 65 when the ironing machine is not in use. The rear closure member 24 extends from the upper face of the legs 18 to below the bases of the frame side members 10 and 11 and carries a flange 25 at its upper face flush 70 with the tops of the table legs 18. The table top 26, preferably made of sheet metal appropriately reinforced, has depending flanges 27 on all sides, the rear flange there- 75 of being pivotally connected to the rear closure member 24 at its upper face 25 by means of the hinge 28. The dependent flanges 27 of the table top are of height sufficient to rest snugly against the tops of the legs when the table top is in its normal horizontal position at the same time housing the upwardly 80 projecting portions of the roll 15 and the shoe 16. The depending flanges 27 are so constructed that their outer faces when the table top is horizontal are flush with all the side members and the legs, thereby eliminating 85 projecting parts. The side members 29 are pivoted about vertical pivots 30 conveniently located directly in front of the rear table legs and are provided with knobs 31 for conveniently swinging them rearwardly. The exposed surfaces of the table top, the depending flanges, the closure members and the legs are preferably enamelled. The legs 18 90 are preferably provided with casters 32 and are made telescopic enabling the height of the combined ironer and kitchen table to be adjusted at will by the operator. Drying racks 34 are conveniently located on the un- 95 100

der side of the table top 26 supported in the depending end flanges.

The roll 15 is rotatably supported upon hollow fixed shaft 35 secured against rotation by means of the set screw 36 in the frame side member 10. The motor supporting yoke 37 is mounted upon the hollow shaft 35 within the periphery of the roll 15. The shaft of the roll driving motor 38 carries the fan 39 and the worm 40. In order to reduce the speed of the motor 38 to that required for effective ironing by the roll, a worm reduction gearing 41 is mounted in the housing 42 bolted to the yoke 37. The worm 40 meshes with the worm gear 43 on the shaft of which worm 44 in turn meshes with worm gear 45. The worm 46 on the shaft carrying worm gear 45 in turn meshes with worm gear 47 keyed to the shaft 48 which is rotatably mounted in the frame side member 11 by means of roll bearing 49. The roll bearing 50 rotatably supports the shaft 48 on the worm gear housing 42. The roll head 51 is pinned to the rotatable shaft 48 while the head 52 is rotatably supported upon the hollow shaft 35 by means of roller bearing 53. Vents 54 are provided in the roll heads, the motor supporting yoke and in the worm gear housing, permitting a current of air to circulate through the roll propelled therethrough with the aid of the fan 39. The current supply leads 55 for the motor pass through the hollow shaft 35 and may be connected to the house mains 56 by means of the switch 57 conveniently located at the front of the machine and readily accessible to the operator.

To the rear of roll 15 and movable relatively thereto, there is mounted the heated ironing shoe 16 carried by the arms 17 and pivotally attached to the upper end thereof by pins 60, permitting the shoe to oscillate into proper seating relationship with the roll. The arms 17 extend downwardly and are rigidly affixed to the shaft 13 rotatably supported in the lower rear portion of the frame side members 10 and 11. To the shaft 13, at any convenient portion thereof, is keyed the arm 61 in the outer end of which carries the disc 62 through which the eccentric rod 63 projects. The free end of the eccentric rod 63 is threaded and is operatively connected to the arm 61 by means of a compression spring 64, the spring cap 65 and the nuts 66. The eccentric rod 63 is pivotally connected to a face of the worm gear 67. The worm 68 meshes therewith and is carried by the shaft of the shoe drive motor 69. The dash-pot button switch 70 conveniently mounted at the front of the machine and readily accessible to the operator carries an arm 71 insulated from the button by means of a non-conductor 72. The dash-pot of the switch includes a cylinder 70' having the piston 71' and spring 73' of switch-button 70 therein, and a valve

72' permitting slow escape of air from the cylinder 70' to release the piston 71' and break the previously closed contact between the arm 71 and the leads 73 and 74 after a predetermined interval. Equivalent timing mechanism for retarding the opening of switch 70 may be employed with equal facility. The rotatable shaft 75 carries fixed thereupon the worm gear 67 and the sleeve 78 electrically insulated therefrom however by means of the sheath 79. The discs 76 and 77 are of a material which is an electrical conductor and are in electrical contact with the sleeve 78 and with the brushes 81 and 82 respectively. The segment 79 has inserted in its periphery and spaced 180° from each other, two segments 80 of any convenient electrical insulation material.

In operating the ironing machine of this combined structure, the table top 27 is pivoted upwardly and rearwardly exposing the roll and shoe. The feed table 22 is thereupon similarly swung upwardly and rearwardly bringing it in to operative position and closely adjacent to the roll 15. Side closure members 29 are then swung outwardly and may be used for supporting the work preparatory to ironing or after ironing. There are no obstructions at the ends of the roll 15 when the side members 29 are in position as shown in Fig. 3 thereby enabling the ironing of material of greater width than the roll upon my improved machine.

Switch 70 is thereupon depressed bringing the arm 71 in contact with the conductors 73 and 74 and closing the circuit from the electric house mains through the shoe drive motor 69. The rotation of worm 68 causes the rotation of worm 67 and shaft 75 at the same time advancing the shoe 16 toward the roll 15. Rotation of shaft 75 carries with it the discs 76 and 77, thereby advancing the insulating segment 80 from beneath the brush 81 and completing the circuit through the house mains and electric motor through the disc 76, sleeve 78, disc 77 and brush 82. Reopening of the switch 70 by its spring 73' is deferred by dash-pot 70'—71' until after the shoe motor 69 has rotated disc 76 sufficiently to disconnect brush 81 and insulating segment 80. However, the motor 69 is still connected to the source of power supply until the other segment 80 contacts with the brush 81 thereby breaking the circuit. The throw of the eccentric rod 63 and the tension of spring 64 are so adjusted that during the rotation of a half revolution of the shaft 75, the shoe 16 is brought into operative contact with the roll 15. The ironing shoe 16 is now resiliently held against the roll 15 by means of spring 64, thereby enabling the ironing of materials of varying widths.

In that the power operating mechanism for the roll and for the shoe are absolutely independent one of the other, the ironing shoe

may be brought into operative position without rotation of the roll. This enables the operator to perform any pressing operation on the machine that may be required, such as pressing of trousers, pleating, etc. The pressure of the shoe against the roll may be varied by the operator by adjusting the tension of spring 64 by bringing up or loosening nuts 66.

10 For the usual continuous ironing of miscellaneous materials, the switch 57 is closed, thereby rotating the roll. The fan 39 mounted upon the roll driving motor shaft prevents over heating of the motor and serves to cool 15 the roll during the continuous ironing operation. The ironed materials pass between the roll and shoe and drop into the trough 20 below the roll from which they are removed at the convenience of the operator.

20 What is claimed is:—

1. In an ironing machine, a supporting member, a roll rotatably mounted thereupon, an ironing shoe, a motor for actuating said shoe to and from the roll another motor for 25 independently driving said roll, and means controlled by movement of the shoe motor for governing the operation of the shoe motor.

2. In an ironing machine, a supporting member, a roll rotatably mounted thereupon, an ironing shoe to co-operate with said roll, power means for actuating said shoe to and from the roll other power means for independently driving said roll, and an electrical switch controlled by movement of said 35 shoe actuating power means for controlling the shoe actuating power means.

3. In an ironing machine, a supporting member, a roll rotatably mounted thereupon, an ironing shoe to co-operate with said roll, a motor, means driven by said motor for moving said shoe into and out of co-operative relation with the roll, a second motor means for rotating the roll and switch means in the 45 circuit of said first motor controlled by movement of said first motor.

4. In an ironing machine, a supporting member, a roll rotatably mounted thereupon, an ironing shoe to cooperate with said roll, a 50 motor, means driven by said motor for moving said shoe into and out of cooperative relation with the roll, a second motor, means for rotating the roll driven by said motor, and an electrical switch controlled by said 55 first-named means for stopping said shoe motor at predetermined positions of said shoe.

5. In an ironing machine, the combination of a rotatable roll, a shoe movable to and 60 from said roll, separate motors for driving said roll and shoe, and an electrical switch controlled by the shoe motor for controlling the said shoe motor.

6. In an ironing machine, the combination 65 of a rotatable roll, a shoe movable to and

from said roll, separate motors for driving said roll and shoe, a manual electrical switch controlling the shoe motor, and a second electrical switch controlled by movement of said driving motor shoe for controlling said shoe 70 motor.

7. In an ironing machine, the combination of a rotatable roll, a shoe movable to and from said roll, separate motors for driving said roll and shoe, a circuit breaker in the 75 shoe motor circuit driven by said shoe motor, brushes engaging said circuit breaker, and electrical connections between said brushes and said shoe motor whereby the movement of the shoe driving motor controls the shoe 80 motor.

8. In an ironing machine, the combination of a rotatable roll, a shoe movable to and from said roll, separate motors for driving said roll and shoe, a switch element driven by 85 said shoe motor, and a second switch element adapted to engage said first switch element and interposed between said motor and a source of power, whereby movement of said switch element by said shoe motor controls 90 the operation of the shoe motor.

9. In an ironing machine, the combination of a rotatable roll, a shoe movable to and from said roll, separate motors for driving said roll and shoe, an electrical switch inter- 95 posed between said shoe motor and the source of power therefor, and driving connections between said shoe motor and said switch, whereby movement of said shoe motor controls the operation of the shoe motor. 100

10. In an ironing machine, the combination of a pair of ironing elements, a motor for moving one of said elements relatively to the other, a disconnect switch actuated by said motor for stopping the motor, a normally open starting switch for said motor adapted to be closed to short circuit the disconnect switch for starting the motor, and means for reopening said normally open switch after a predetermined time of closure. 110

In witness whereof, I hereunto subscribe my name this 23 day of Aug., 1927.

CHARLES E. REDDIG.

CERTIFICATE OF CORRECTION.

Patent No. 1,837,584.

Granted December 22, 1931, to

CHARLES E. REDDIG.

It is hereby certified that error appears in the printed specification of the above numbered patent requiring correction as follows: Page 2, line 14, for the numeral "40" read 41; page 3, line 70, claim 6, strike out the word "shoe" first occurrence and insert same after "said" in line 69, and line 88, claim 8, for the misspelled word "betwen" read between; and that the said Letters Patent should be read with these corrections therein that the same may conform to the record of the case in the Patent Office.

Signed and sealed this 23rd day of February, A. D. 1932.
